UNITED STATES PATENT OFFICE.

HENRY W. HILDEBRAND, OF DENVER, COLORADO.

AUTOMATICALLY-OPERATING FIRE-EXTINGUISHER.

No. 811,221.

Specification of Letters Patent.

Patented Jan. 30, 1906.

Application filed June 21, 1905. Serial No. 266,289.

To all whom it may concern:

Be it known that I, HENRY W. HILDEBRAND, a citizen of the United States of America, residing in the city and county of Denver and State of Colorado, have invented a new and useful Automatically-Operating Fire-Extinguisher, of which the following is a specification.

My invention relates to an improved fire-extinguisher; and the objects of my invention are, first, to provide an automatically-operating fire-extinguisher; second, to provide an automatically-operating fire-extinguishing system; third, to provide a fire-extinguisher having an acid-gas-spraying device; fourth, to provide a fire-extinguisher provided with an interior cylinder arranged to form an annular gas-discharging space within it; fifth, to provide a safe, durable, simple, automatic fire-extinguisher that is adapted to be used singly or in series and be permanently positioned within or suspended from the ceilings of rooms and that is adapted to operatively use the chemical fire-extinguishing solutions in common use. I attain these objects by the mechanism illustrated in the accompanying drawings, in which—

Figure 1 is a perspective view of my improved fire-extinguisher arranged in an automatically-operative series or system that is adapted to protect a large room. Fig. 2 is a vertical section of a single extinguisher suspended to the ceiling of a room by a fusible hook. Fig. 3 is a longitudinal section of the locking-bolt I employ to hold the extinguishers of the system in position for operative use. Fig. 4 is plan view of one of the cans. Fig. 5 is a longitudinal vertical sectional view illustrating a modification of my device in which the cans are placed in boxes between the joists and beneath the floor of a building, the boxes being provided with a bottom composed of hinged doors which are normally closed by a spring-latch, the chain which supports a can in one box being connected with the spring-latch in the adjoining box. Fig. 6 is a similar view showing the series of latches tripped and the cans dropped to an operative position. Fig. 7 is a diagram illustrating the manner of operating a series of extinguishers.

Similar numerals of reference refer to similar parts throughout the several views.

Referring to the drawings, the numeral 1 designates a body of a can or a receptacle of any suitable form, 2 its bottom member, and

3 the top member of the can. The top and bottom of the can are secured to the body part in any suitable manner. I form the top member 3 of the can with two flat step portions 4 and 5 and two short vertical portions 6 and 7, the upper vertical portion 7 of which forms the neck of the can. A thread 8 is formed on the outer surface of the neck 7, and a cap 9 is threaded to the neck. 65

To the inside surface of the vertical portion 6 of the cap I secure, preferably by solder, one end of a cylindrical tube 10, the opposite end of which extends to close to, but not quite to, the bottom of the can, a small 70 annular space 11 being left between the bottom of the can and the lower edge of the cylinder. This cylinder divides the interior of the can into two compartments that are connected together at the bottom through the annular 75 space below the lower edge of the cylinder, and through the surface of the step 4 I form a plurality of gas and water spraying apertures 12. I preferably make the can round and form a circumferential row of small holes 80 or perforations through the step, placing them quite close together. These perforations form discharge-apertures for the circumferential concentric space between the side of the can and the outer surface of the 85 cylinder 10.

To the central portion of the inside of the cover I secure a short depending cone 13, and to the surface of the cone I secure at equal distances apart several depending arms, 90 brackets, or strips 14, to the lower ends of which I secure a cap 15. The interior of this cap is threaded. To this cap I secure a small glass receptacle or bottle 16, preferably by forming a thread on its neck to screw tightly 95 into the cap, and in the top of the cap I form a discharge-aperture 17, through which the apex of the cone extends, and I make this aperture a trifle larger than the diameter of the cone at the point it passes through the 100 top of the bottle in order to form a discharge-aperture for the contents of the bottle all around the cone. To the center of the bottom of the can I secure an eye 18. To this eye I secure one end of a cord or chain 19, the 105 opposite end of which I secure to an eye 20, which I secure to the ceiling of a room. On the top of the cap of the can I form an eye 21, and to the ceiling 22 of the room in which the can is hung I secure adjacent to the eye 20 110 an eye 22^a, to which I hang one end of a fusible hook 23, the opposite end of which is

connected to the eye of my fire-extinguisher, as shown in Fig. 2, when it is to be used singly for a room, in which case one or several may be suspended independent of each other in a room. The body of the can is provided with a supply of the solution 24 usually used in chemical fire-extinguishers, preferably a solution of bicarbonate of soda and water, and the bottle is provided with a supply of acid, the proportion of acid to the volume of solution being such a determinate amount as will form a suitable chemical fire-extinguishing gas when they are mixed together. On the step 4 over the perforations I place a washer 24^A, of paper or of any other suitable material, and then stick and coat the washer with a coat of shellac or with any other suitable material. The cap is also fitted or made perfectly air-tight on the top of the can, and the solution and acid are thus prevented from evaporating.

In Fig. 1 I illustrate my improved fire-extinguisher arranged in series. In this arrangement the fire-extinguishing can, the liquids in the can, the chain, and the fusible hook are the same as illustrated in Fig. 2; but the fusible hook is hung on the locking end 25 of a spring locking-bolt 26. This spring locking-bolt comprises a casing 27, which is secured to the ceiling 22, a bolt 26 and a coiled spring surrounding said bolt in the aperture in said casing, in which said bolt is slidably and operatively mounted. Such a spring-bolt is in common use and in itself does not form any part of my invention. The opposite end of the bolt from its locking end is provided with an eye 28, and to this eye I attach one end of a cord 29, preferably a wire cord. This cord extends to and is connected to the end of the chain 19, which is supported by and passes over a small pulley or sheave 30, which is pivotally mounted in a yoke 31, that is secured to the ceiling, and each fire-extinguishing can is connected to the one adjacent to it, and so on around to the first can hung. All the cans are in this way connected together. Thus assuming that the can 32 of Fig. 1 was the first can to be hung from the ceiling, it would be connected to can 33 by the chain 19, which would pass over the pulley 30 and would connect to the spring-bolt 26, from which the can 33 is supported by its fusible hook 23, and the can 33 is then connected in the same manner to the can 34, and the can 34 is connected in the same manner to the can 35, and the can 35 is connected in the same manner to the can 32, from which the series started. Then if a fire starts under or adjacent to any one its fusible hook would melt and it would drop and hang cap down from the end of its chain, and the weight and jerk of its drop would pull on its cord and pull back the spring-bolt out of the fusible hook of the can next to it in the order of the operative dropping arrangement, and as the next can drops it pulls on its connect-

ing-cord with the next can and frees it, and so on around to the can that first dropped. Consequently they are all dropped into operative fire-extinguishing position by the melting of the fusible hook of any one can in the system. Thus if a fire should start adjacent to the can 32 it would by the weight of its drop set off the can 33, then 34, and then 35, which would all follow in almost instantaneous succession. Thus any number of fire-extinguishers could be arranged in any order desired to the under side of a ceiling, and in a convenient point in the system a spring alarm-bell 36 can be connected by a cord or wire 37 to one of the cords 29 or chains 19 in such a manner as to set the alarm-bell off when the fire-extinguishers drop. While I have illustrated this alarm-bell attached to the ceiling, it can be placed in the office of a factory or manufacturing plant where the system is in use, or in any place where it would attract the attention of a watchman, or to a telephonic fire-alarm system that connects directly with the fire department of the city or town in which the building or buildings are located using my fire-extinguisher.

In Figs. 5 and 6 I illustrate my automatic system substantially as shown in Fig. 1, with a few slight modifications in the dropping mechanism inclosed in boxes which are placed between the ceiling-joists and secured in position there in any suitable manner. The boxes are adapted to hold the fire-extinguishers and are arranged singly or in series in any predetermined operative order between the floor-joists or ceiling-joists of rooms level with the plastered ceiling which extends between them, as shown in Fig. 5. The bottom of each box is provided with a pair of trap-doors 38 and 39, which are hinged to the opposite corners of the box by the hinges 40 and 41. These double trap-doors are locked in a closed position by a combination of three hooks 42, 43, and 44. The hook 42 is a fixed non-fusible metal hook that is permanently fixed in the lower side edge of the box at the side of the doors and depends below them with its point arranged out of their opening path. Above this hook within the box I pivotally secure a spring locking-bolt 26 by a screw 46, which passes loosely through a lug 47, formed on the casing 27 of the spring locking-bolt, which is similar in construction to the locking-bolt of Fig. 3, with the exception that it is pivotally secured on one screw to tilt inside of the box instead of being rigidly secured as it is in Fig. 1, and to a lug 47^A, which is formed on the lower side of the locking-bolt's casing 27, I secure one end of a fusible hook 43, the hook end of which depends and normally hooks under the hook end of the hook 42, and the fusible hook is made of a length to hook under the hook 42. The door 38 is provided with a rabbeted lip 48, and the door 38 when closed fits up under and against the edge of 130

the door 39, which rests on top of it, and in order to hold the door 38 normally closed I secure one end of a hook 44 to it. The opposite or hook end of the hook 44 is arranged 5 to hook over the locking-end 25 of the spring-bolt 26, and when this hook 44 and the fusible hook 43 are both connected to the spring locking-bolt it will stand substantially horizontally in the box. The fire-extinguishing 10 can is placed in the box and is set on top of the trap-doors, and the free end of the chain 19, that is connected to the bottom of the can, is connected to a pulley 51, that is pivotally mounted in a yoke 52, that is secured to the 15 inside of the top of the box, and the chain 19 extends to the next forward box 45 of the system and is secured to the eye 28 at the rear end of the locking-bolt 26 of the box 45. In this arrangement the fusible hook at the top 20 of the can is dispensed with. A single box and fire-extinguisher can be used in this system if the can-chain is secured to the top of the box or to the ceiling just the same as with the single extinguisher shown in Fig. 2 if it 25 is desired to conceal the can from view; but it is more especially adapted to a series of fire-extinguishers, and in this case the chain 19 is secured to the eye 28 at the rear end of the spring-bolt 26 and extends through the 30 box and to the pulley or sheave 51 of the next box 45^a and fire-extinguishing can in the rear, the same as shown in Fig. 1. In order to operatively arrange the cans in the box, the can is first placed in the box, then the doors are 35 simultaneously closed with the locking end of the spring locking-bolt, the fusible hook which hangs below the ceiling is hooked under the fixed hook 42, and the two hooks—that is, the door-hook and the fusible hook— 40 in connection with the spring locking-bolt, firmly secure the doors in a locked position until the fusible hook melts. Then when a fire starts the fusible hook melts and the weight of the can pulls down on the doorhook 44 and also on the end of the locking-bolt, causing the locking-bolt and its casing 45 27 to pivotally tilt on its pivotal screw. Then the hook 44 will slip off of the end of the locking-bolt and the doors and can will drop, and 50 the can will fall through the doors and hang downward at the end of its chain. This system of connecting the boxes and fire-extinguishers in series in a successively-operating automatic system is substantially the same as 55 that shown in Fig. 1.

In Fig. 7 I have illustrated by means of a diagram the manner of operating a series of boxes or housings so that all the boxes in the series will be operated by the dropping of any 60 one of the cans. The chain 19 at the end of each row of boxes connects by bell-cranks 19^a with the next succeeding row of boxes, so that when a fire starts under any one of the boxes the falling of the can due to the melting of the 65 fusible hook will operate the box next in or-

der of movement and each succeeding box will be operated until the box is reached where the fire started. Thus, supposing the box X is the first to be operated by the fire, the remaining boxes will be affected as indicated 70 by the arrows. My invention, however, contemplates any system of connecting these fire-extinguishers into automatic operative relation that will enable any one fire-extinguisher in the series when its fusible hook is melted 75 by the heat of a fire to automatically precipitate all of the others in substantially instantaneous successive order. My improved fire-extinguisher operates to extinguish a fire in the following manner: When a can falls, it 80 turns upside down and hangs with its cap downward at the end of its supporting-chain. The acid runs out of the bottle and mingles with the solution, thus forming a suitable chemical fire-extinguishing gas which generates 85 pressure and forces the sealing-washer from the step 4 and from over the spraying-apertures 12, from which the gas and solution escape and under its natural pressure sprays downward and flows around a considerable 90 area below and around the can and extinguishes, or at least dampens, checks, and deadens any fire it comes in contact with, while the alarm calls attention and assistance. 95

My invention is simple and inexpensive to install as an automatic system in factories, manufacturing plants, establishments, shops, warehouses, and private residences, and while I have illustrated and described the preferred construction and arrangement of it, both as a 100 single and as a multiple automatic fire-extinguisher, I do not wish to be limited to the constructions and arrangements shown, as there are many ways in which it can be operatively applied without departing from the spirit of 105 my invention.

Having described my invention, what I claim as new, and desire to secure by Letters Patent, is—

1. In a fire-extinguisher, a main receptacle 110 containing a supply of solution, a stepped top portion to said main receptacle, a cap secured to said stepped top portion, a cylinder in said main receptacle, to near the bottom of said main receptacle and adapted to divide said main receptacle into two compartments, a connecting-space between said two compartments below the lower edge of said cylinder, and the bottom of said receptacle, a circumferential row of apertures in said stepped top portion of said receptacle, leading into the space in said receptacle separated from the main body by said cylinder, a small receptacle in said main receptacle containing a supply of acid, proportionate to the amount of solution in said 115 main receptacle, and an acid-outlet in said small receptacle, as set forth.
2. In a fire-extinguisher, a main receptacle 120 containing a supply of solution, a stepped top portion to said main receptacle, a cap secured 125 by said cylinder, a small receptacle in said main receptacle containing a supply of acid, proportionate to the amount of solution in said main receptacle, and an acid-outlet in said small receptacle, as set forth.
3. In a fire-extinguisher, a main receptacle 130 containing a supply of solution, a stepped top portion to said main receptacle, a cap secured

- to said stepped top portion, a cylinder in said main receptacle, to near the bottom of said main receptacle and adapted to divide said main receptacle into two compartments, a connecting-space between said two compartments below the lower edge of said cylinder, and the bottom of said receptacle, a circumferential row of apertures in said stepped top portion of said receptacle, leading into the space in 5 said receptacle separated from the main body by said cylinder, a small receptacle in said main receptacle containing a supply of acid, proportionate to the amount of solution in said main receptacle, an acid-outlet in said 10 small receptacle, and an acid-distributer in the outlet of said small receptacle, as set forth.
3. In a fire-extinguisher, a main receptacle, provided with a circumferential portion extending from its top portion to near its bottom portion, and adapted to divide its interior into two connecting-compartments, a supply of solution in said receptacle, a plurality of perforations in the top of said receptacle leading into the outer compartment, a cap secured 15 to the top of said main receptacle, a cone depending from the bottom of said cap, a small receptacle secured to said cone, and depending into the central portion of said main receptacle, and containing a supply of 20 acid, and an outlet-aperture in said small receptacle surrounding said cone, as set forth.
4. In a fire-extinguisher, a main receptacle, provided with a circumferential portion extending from its top portion to near its bottom portion, and adapted to divide its interior into two connecting-compartments, a supply of solution in said receptacle, a plurality of perforations in the top of said receptacle leading 25 into the outer compartment, a cap secured to the top of said main receptacle, a cone depending from the bottom of said cap, a small receptacle secured to said cone, and depending into the central portion of said main receptacle, and containing a supply of acid, an outlet-aperture in said small receptacle surrounding 30 said cone, an eye secured to the top of said can, a fusible hook secured to said eye and arranged and adapted to be hung and to depend said fire-extinguisher from or in proximity to a ceiling, and a chain or cord secured at one end to the bottom of said receptacle, and at its opposite end to or adjacent to a ceiling, as set forth.
5. In a fire-extinguisher, a main receptacle, having a stepped top portion, a cap secured to 35 said top portion, a fusible hook connected to said cap, an eye or hook attached to or adjacent to a ceiling to which said fusible hook is adapted to be attached, whereby said receptacle is suspended from or adjacent to a ceiling, and a cord or chain secured at one end to the bottom of said receptacle, having its opposite end secured to or adjacent to a ceiling, and adjacent to said fusible hook, as set forth.
6. In a fire-extinguisher, a main receptacle, 40

divided into two concentrically-arranged compartments, connected together at the bottom portion of the receptacle, and containing a supply of solution, a plurality of discharge-apertures in said receptacle, entering the outer concentric compartment, and arranged to be normally sealed, a small receptacle depending in the center of said main receptacle, an outlet in the top of said receptacle, a supply of acid in said small receptacle, a fusible hook 70 connected to the top of said main receptacle, and adapted to suspend said main receptacle, in proximity to a ceiling, and a chain secured at one end to the bottom of said main receptacle and in proximity to a ceiling at its opposite end close to said fusible hook, and adapted to hold said main receptacle in an inverted position when said fusible hook melts, and mix said acid and solution together in said main receptacle, as set forth.

7. In a fire-extinguisher, the combination of a solution-holding receptacle or can divided into two concentric compartments, by a cylindrical partition, extending from its top to close to its bottom, and containing a connecting annular space below the edge of said cylindrical partition, a stepped top to said receptacle, containing a circumferential row of apertures entering the outer compartment of said receptacle, a cap secured to the top of said receptacle, a small acid-holding receptacle or bottle in said main receptacle depending from said cap and provided with a discharge-aperture positioned above said supply of solution in said main receptacle, a conical acid spreader or distributor extending loosely into said acid-discharge aperture, a fusible hook connected to the top of said main receptacle or can, an eye connected to said hook and adapted to be connected to a ceiling, and adapted to depend said main receptacle below a ceiling of a room in an upright position, a chain secured at one end to the bottom of said main receptacle, and to a ceiling, at its opposite end, in proximity to said fusible hook, and adapted to depend said main receptacle in an inverted position when said fusible hook melts, as set forth.

8. In a fire-extinguisher, the combination of a can having a stepped top portion, containing a mouth, a cap threaded to the mouth, and a cylindrical partition in said can adapted to divide it into two compartments, and a circumferential row of discharge-perforations extending through one of the steps of said top portion and provided with an automatically-removing seal, adapted to normally keep them sealed, when can is in position of disuse.

9. In a fire-extinguisher, the combination of the solution-holding can, having the stepped perforated top, the cap, the two compartments 125 connected at the bottom of said can, with the small acid-holding bottle in said can having a discharge-outlet, the conical acid-distributer extending into the discharge-aperture of said acid-holding bottle, means, including a fusi- 130

ble hook secured to the top of said can, adapted for suspending said can from a ceiling, and means, including a cord or chain attached at one end to the bottom of said can, for holding 5 said can from a ceiling in a depending position, as set forth.

10. In a fire-extinguisher, the combination of the can provided with a supply of solution, and containing two compartments connected 10 together at the bottom of the can, the circumferential row of discharge-apertures in said can, and the washer-seal over said apertures, with the cap threaded to the top of said can, the conical distributor connected to the bottom of said cap, the depending arms secured to said conical distributor, the threaded cap-supported aperture surrounded with an annular space all around said conical distributor, the bottle provided with a supply of acid arranged to screw into said cap, the fusible hook connected to the top of said can, means for connecting said fusible hook to a ceiling, the chain connected at one end to the bottom of said can, and means for connecting the opposite 25 end of said chain to a ceiling adjacent to said fusible hook, as set forth.

11. In a fire-extinguisher, the combination of the solution-holding can having a removable cap, and normally sealed discharge-apertures, with a conical acid-distributer depending apex downward from said cap, a plurality of arms secured to said conical distributer, a threaded cap supported by said arms, a discharge-aperture surrounding said conical acid-distributer and adapted to form a discharge-space of predetermined area around said conical distributer above the level of the solution in said can, discharge-spaces between said arms, and a bottle provided with a supply of acid threaded to said cap, a fusible hook connected to the top of said can, means for securing said fusible hook to a ceiling to depend said can therefrom in an upright position, a chain or cord secured at one end to the bottom 45 of said can, and means for securing the opposite end of said chain or cord to a ceiling to stop and hold said can in an inverted position when said fusible hook melts, and it drops from the ceiling, as set forth.

50. 12. In a fire-extinguisher, the combination of a series of fire-extinguishers, comprising a receptacle having two concentric compartments, connected at the bottom with each other, and holding a supply of solution and having a normally sealed plurality of apertures through said can into the outer compartment, and an acid-holding receptacle in said receptacle, adapted to discharge its acid contents into the solution of said receptacle 55 when said receptacle is turned into an inverted position, a fusible hook to each fire-extinguishing receptacle, a chain secured at one end to each fire-extinguishing receptacle, a pulley in said ceiling, arranged to support the opposite 60 end of said chain, a cord attached to the opposite

site end of each chain of each fire-extinguisher, and a spring-bolt secured to the ceiling and connected at one end to said cord and having the fusible hook of each fire-extinguisher receptacle in the system hooked over its operative bolt end, as set forth. 70

13. In a fire-extinguisher, the combination of an automatic-operating fire-extinguishing system adapted to be secured below or in the ceiling-joists of rooms, comprising a plurality 75 of main receptacles, each containing two compartments connected at the bottom of said receptacle, and containing a supply of solution, a small receptacle in each main receptacle, containing a supply of acid, and having a discharge-outlet above the solution of said main receptacle, a spring-bolt secured in juxtaposition to a ceiling at each point a fire-extinguishing receptacle is to be placed, a fusible hook secured to the upper end of said fire-extinguishing receptacle adapted to be hooked over the locking end of said spring-bolt, a chain secured at one end to each fire-extinguishing receptacle in the series, a pulley secured in juxtaposition to a ceiling for supporting the 80 opposite end portions of said chain, and a cord secured to the pulley end of said chain of each fire-extinguishing receptacle at one end and at its opposite end secured to the rear end of said spring-bolt, as set forth. 85

14. In a fire-extinguisher, the combination of a plurality of the fire-extinguishing receptacles, and their fusible hooks, and tilting chains, arranged in any desired system below or between the ceiling-joists of rooms, 100 and means, including a spring-bolt, for operatively precipitating all of said receptacles in successive order when the fusible hook of any one receptacle is melted, as set forth. 95

15. In a fire-extinguishing system, a plurality of cans, each containing normally sealed discharge-apertures when in an upright position, and containing a supply of solution, a bottle in each of said cans, containing a supply of acid, said bottle containing a discharge-aperture positioned above said solution when said can is in an upright position, a fusible hook at the top of each of said cans, in said system, means for operatively positioning said fusible hooks and cans in close proximity to a 110 ceiling, and means, including a spring-operated bolt, for operatively precipitating the cans of the system in successive order, when the fusible hook of any one of the cans in the system is melted, and means for limiting the 120 precipitative movement of said cans, as set forth.

16. In a fire-extinguisher, the combination of a plurality of the fire-extinguishing cans housed between the ceiling-joists of a room, 125 trap-doors in the bottom of said housing, a spring-bolt pivotally secured in said housing to tiltingly swivel, and arranged adjacent to said trap-doors, a hook connected to hold said doors closed and arranged to hook over the 130

locking end of said spring-bolt, a fire-extinguishing can resting on said trap-doors, a cord secured at one end to the bottom of each of said cans in said housing, a pulley in said housing arranged to support the opposite end of said cord, a fixed hook depending from said housing, a fusible hook connected to the rear end of said spring-bolt of each can, and arranged to depend therefrom and hook under
10 the fixed depending hook, and a chain extending from the rear end of said spring-bolt, and connected to the cord of the adjacent fire-extinguishing can, said chains of said spring-bolts and said cords of said cans being connected together in successive order throughout the system, so that when the fusible hook of any one housing melts its spring-hook will tilt and the trap-doors and can will drop and the jerk of the can on its cord will pull the
20 spring-bolt free of the trap-door hook in the housing of the adjacent fire-extinguishing can, and the drop of this can will trip the spring-bolt and doors of the next can in the order of their arrangement around the circuit of the
25 system to the can whose fusible hook melted, as set forth.

17. In a fire-extinguisher, the combination of the system of fire-extinguishing cans and their housing-boxes, provided with trap-doors arranged to support the fire-extinguishing cans, the trap-door hooks, the pivotally-tilting spring-bolts in said boxes adapted at their locking ends to lock to the bolt ends of said spring-bolts, the fixed hooks in the bottom of said boxes, the fusible hooks connected to the rear ends of said spring locking-bolts, the drop-limiting cords attached to the bottoms of said fire-extinguishing cans, the pulleys in the top of said boxes for supporting said cords, and the chains secured to the rear ends of said spring locking-bolts, and connected to the spring tilting-bolts of the boxes of the adjacent fire-extinguishing cans in the order of their arrangement, around the system, as set forth.

In testimony whereof I affix my signature in presence of two witnesses.

HENRY W. HILDEBRAND.
